UNITED STATES PATENT OFFICE

MELVIN DE GROOTE, OF ST. LOUIS, AND LOUIS T. MONSON, OF MAPLEWOOD, MISSOURI,
ASSIGNORS, BY MESNE ASSIGNMENTS, TO TRETOLITE COMPANY, OF WEBSTER
GROVES, MISSOURI, A CORPORATION OF MISSOURI

PROCESS FOR CONDITIONING PETROLEUM OILS

No Drawing.

Application filed March 3, 1930. Serial No. 432,975.

This invention relates to a process for conditioning petroleum oils of the kind in which water or brine, either in a free state or in an emulsified state, is combined with the oil. The process is applicable to petroleum oils that contain water which can be removed or separated from the oil by a settling operation or by heating the oil, and the process is also applicable to petroleum oils of the kind commonly referred to as "cut oil", "roily oil", "emulsified oil" and "bottom settlings", which require treatment with a chemical demulsifying agent, electrical dehydrator or similar medium to dehydrate the oil and make it suitable for commercial use or to satisfy commercial requirements.

We do not contend that our process will of itself break or resolve petroleum emulsions of the water and oil type, in which fine droplets of naturally-occurring waters or brines are dispersed in a more or less permanent state throughout the oil constituting the continuous phase of the emulsion, but our process will materially assist in the breaking or resolution of such petroleum oils by processes, apparatus or procedure of the kind now commonly employed for this purpose. Due to the low cost of our process it is commercially feasible or practicable to use our process in conjunction with processes or apparatus of the kind employed to dehydrate petroleum emulsions, and it is also adaptable for use as a preliminary step or conditioning step in the treatment of petroleum oils that contain water which can be separated or removed with minimum trouble and expense and without resorting to the use of demulsifying agents, electrical dehydrators or the like.

Briefly described, our process consists in subjecting petroleum oil containing water or brine, either in a free state or emulsified state, to the action of a conditioning agent that contains, comprises or is composed of a substance which we will hereinafter refer to as "sulfur dioxide extract", so as to assist in the action of subsequent procedure that is employed to effect the removal of such water or brine, which subsequent procedure may consist simply of settling the oil or heating the oil, or treating the oil with a chemical de-

mulifying agent or passing it through an electrical dehydrator, as is necessary in the dehydration of cut oil, roily oil and similar petroleum emulsions. The conditioning agent may be used in any state and any preferred procedure may be employed to bring said conditioning agent into contact with the oil being treated. Usually the conditioning agent will be introduced into a producing well by pouring it down the casing or tubing of the well, or the treating agent will be introduced into an oil line through which oil is flowing, or introduced into a tank in which the oil is stored. It is only necessary to use a very minute quantity of the conditioning agent, and in practicing our process, the amount of conditioning agent that is required will vary according to the nature or characteristics of the particular oil being conditioned. As a typical example of our process, we will say that when the conditioning agent is used in a concentration of about 1 part of agent to 1,000 parts of oil being treated, the action of the subsequent treating procedure that is employed to effect the removal of water or brine from the oil will be greatly enhanced or improved. At other times as little as 1 part of agent to 5,000 parts of oil may be sufficient.

The sulfur dioxide extract contemplated by our process is an oil-soluble substance, and it is obtained or produced from petroleum distillates or other suitable hydrocarbon bodies, by means of liquid sulfur dioxide. One source of supply of such material is a by-product or residuum obtained in the operation of purifying petroleum distillates by the well known "Edeleanu process," described in U. S. Patent No. 911,553, to Lazar Edeleanu, dated February 2, 1909. Said Edeleanu process, briefly described, consists in agitating petroleum distillate with liquid sulfur dioxide at a low temperature, and then permitting the mass to separate into two layers, the lower of which is a solution of aromatic and unsaturated compounds in liquid sulfur dioxide. The said solution may also contain any sulfur-containing compounds originally present in the petroleum distillate. After withdrawing the said solution from the reac-

tion vessel, the sulfur dioxide is recovered by driving it off at a higher temperature, leaving a residuum which we will refer to as "a sulfur dioxide extract". The sulfur dioxide 5 may be re-cycled for further use in the process.

The sulfur dioxide extract, which appears as a residuum, consists of a mixture of compounds which contains only a trace of sulfur dioxide, and it is the "sulfur dioxide extract" that we prefer to use in practising our process. It contains chiefly aromatic bodies and unsaturated bodies. Some of the aromatics may be mono-cyclic and some poly-15 cyclic. Some may be hydrogenated aromatics. The unsaturated bodies may be of the aliphatic or of the cyclic series. In an average sample of residuum or sulfur dioxide extract of the kind above referred to, it 20 is probable that all of these various types are present in larger or smaller quantities, although specific samples would vary in the percentage of each constituent present. For example, if Borneo petroleum distillate were 25 subjected to treatment by the Edeleanu process, the residuum, or sulfur dioxide extract obtained would be expected to consist largely of aromatic bodies, whereas, if West Texas petroleum distillate were subjected to treatment 30 by the Edeleanu process, the residuum, or sulfur dioxide extract obtained, would contain a smaller proportion of aromatics.

While we prefer, in practising our process, to use a conditioning agent that comprises, 35 contains, or is composed of sulfur dioxide extract obtained as a by-product in the purification of petroleum distillate by the Edeleanu process, due to the low cost of such sulfur dioxide extract, we wish it to be understood that 40 it is immaterial, so far as our invention is concerned, how or from what source the sulfur dioxide extract is obtained. We have obtained good results with a conditioning agent composed of sulfur dioxide extract obtained in the purification of a distillate obtained from West Texas,--crude petroleum-- 45 by the use of liquid sulfur dioxide at a low temperature.

Approximately 10% of the sulfur dioxide 50 extract could be distilled at a temperature range of 360° F. to 390° F., and as the temperature was increased, the percentage of the sulfur dioxide extract distilled increased 55 in about the following ratio, i. e.:

	Per cent
390-400° F.	11-20
401-410° F.	21-30
411-421° F.	31-40
422-430° F.	41-50
431-443° F.	51-60
444-455° F.	61-70
456-472° F.	71-80
473-490° F.	81-90
Above 490° F.	91-100

The specific gravity of the sulfur dioxide extract obtained was approximately 0.899 at 60° F. It contained only a trace of bodies extractable by means of sodium hydroxide. Strong sulfuric acid dissolved a portion of it 70 with the evolution of heat. Oleum acted more vigorously, but in a similar fashion. The solution constituting the lower acid layer of the reaction mass contained sulfonic acids or similar bodies soluble in water. By means 75 of 25% by volume of 66° Baumé sulfuric acid, 11% of the sample was dissolved. Since no exact analysis of the material can be made to determine the amount of each member of the various homologous series present, no more 80 complete characterization of the material can be given.

Having thus described our invention, what we claim as new and desire to secure by Letters Patent is:

1. A process for conditioning petroleum oil that requires treatment to effect the removal of brine or water from same, which consists in subjecting the oil, prior to such treatment, to the action of a soluble conditioning agent, comprising a mixture of aromatic and unsaturated petroleum bodies extracted from petroleum by means of liquid sulfur dioxide.

2. A process for conditioning petroleum oil 95 that requires treatment to effect the removal of brine or water from same, which consists in subjecting the oil, prior to such treatment, to the action of a minute quantity of a soluble conditioning agent, comprising sulfur dioxide 100 extract of the Edeleanu purifying process.

3. A process for conditioning petroleum oil that requires treatment to effect the removal of brine or water from same, which consists 105 in subjecting the oil, prior to such treatment, to the action of a minute quantity of a soluble conditioning agent, comprising sulfur dioxide extract having a specific gravity of approximately 0.899 at 60° F. and a boiling 110 range of 360° F. to over 490° F.
